Jonathan Lee Stanley & James C. Howard, Winthrop, Maine
Letters Patent

The schedule referred to in their Letters Patent and
making part of the same, containing a description in the
words of the said Jonathan Lee Stanley & James Copeland
Howard themselves of their improvement in the Endless
Band for Horse Power.

To all to whom these presents shall come,
Be it known that we, Jonathan Lee Stanley & James
Copeland Howard, of Winthrop in the County of Kennebec
and State of Maine, have invented a new and useful im-
provement in the Endless Band for Horse Power, and that the
following is a full and exact description of the construction
and operation of the said machine as invented by us -

We make a band of stout sole leather, fourteen
inches more or less, as occasion may require in width. To this
band we attach board, or slats of wood of a suitable length &
thickness. The ends of the band then being connected together,
an endless band of lag is then formed. This band we
pass over drums of suitable size fixed in a frame, there be-
ing a ledge or shoulder projecting upward at the end of
each drum to prevent the lag, or band from running off.
To prevent the sagging of the band, we adopt the following
plan or arrangement of rollers, viz., next to the drum at the
head of the machine we pass a shaft across the frame,
resting on each side of it. On each end of this shaft, but
within the frame, we place a roller or pulley. Next to this
shaft, but within the frame we insert a cylinder of a
length nearly sufficiently to fill the space between the ro-
llers aforesaid, its guides passing by them, and resting on
the sides of the frame. Next to this cylinder, we place a
shaft with pulleys on the ends as at first - then a cylinder

and so on alternately, until the space from the drum to drum is filled.

Reference to the plate - A (Fig 1) is the frame, B B the drums on which the band of logs passes, C C the pulleys - b b, the cylinders. Fig 2 shows the sole leather band with some of the logs attached.

Claims

What we claim as our improvement, and for which we request an exclusive right, is, 1. Our plan of making and using a band of sole leather as above specified. 2. our plan or system of friction rollers and cylinders for preventing the sagging of the Endless Band and to diminish the friction of the drums as above specified.

In testimony that the above is a true specification, as above described, of our said improvement, we have hereunto set our hands, this first day of December
